UNITED STATES PATENT OFFICE

JOHN F. O'CONNOR, OF CHICAGO, ILLINOIS, ASSIGNOR TO W. H. MINER, INC., OF CHICAGO, ILLINOIS, A CORPORATION OF DELAWARE

BRAKE MECHANISM

Application filed February 15, 1926. Serial No. 88,193.

This invention relates to brake mechanisms.

An object of the invention is to provide a hand brake for railway cars and other vehicles having means for quickly taking up the slack in the brake chain, and thereafter automatically increasing the leverage ratio pull upon the brake chain during the final application of the brake.

10 Other and further objects of the invention will more fully appear from the description and claims hereinafter following.

In the drawings, Fig. 1 is a fragmentary end elevation of a railway car showing my 15 invention applied thereto. Fig. 2 is a horizontal sectional view of the invention, taken substantially upon the line 2—2 of Fig. 1, and showing parts of the mechanism in top plan. Fig. 3 is a horizontal sectional view 20 taken on the line 3—3 of Fig. 1, also showing parts of the mechanism in top plan. And Fig. 4 is a fragmentary side elevational view of the brake rod and pulley showing the 25 double ended chain looped thereover and connected to parts of the brake mechanism illustrated in section. Fig. 5 is a top plan with staff in section.

Referring to the drawings, 10 indicates the end sill of the railway car or other portion of 30 the car structure, and 11 indicates the brake platform. Extending through the platform is the usual driving staff or mast 12, said staff being provided with a ratchet wheel 13 above the platform 11, with a pawl 14 pivotally 35 mounted on the platform and adapted to engage the ratchet wheel 13 in the usual manner. A hand wheel 15 is mounted on the upper end of the brake staff to be used for imparting rotation thereto.

40 The brake staff 12 extends downwardly through a bracket 16 secured to the end sill and is rotatively mounted therein, the lower portion of the staff below the bracket 16 having a pinion 17 affixed thereto. Said pinion 45 is adapted to mesh with the upper teeth of an internal ring gear member 18, which is mounted to turn about a shaft 19, which is connected to the support 20 and extends downwardly therefrom. Mounted on the 50 shaft 19 below the ring gear member 18 is

a cylindrical rotatable member 21 provided with superposed radially extending arms 22, the lower end of the member 21 having an offset 23 adapted for a purpose hereinafter explained, said offset being provided with a 55 trunnion 24 co-axially disposed with reference to the shaft 19 and rotatably mounted in the brake step 25.

Rotatably mounted adjacent the outer ends of the laterally extending arms 22, and between the same, is a rotatable element providing a winding drum 26, said winding drum having an ear 27 thereon to which one end of a brake chain 28 is connected, said chain extending over a pulley 29 rotatably 60 mounted on the brake rod 30, said chain being doubled back, as indicated at 31, and connected to an extension 32 formed on the outer end of the lower arm 22. The step 25 is provided with a stop 33 against which the lower 65 arm 22 is adapted to normally abut and restrain swinging movement thereof toward the brake rod. The upper end of the winding drum is provided with a gear 34 adapted to mesh with the lower teeth 35 of the ring 70 gear member 18.

In operation assuming that the brake chain is slack, the pull upon the two ends of the 75 brake chain by the pull rod is sufficient to hold the lower arm 22 against the stop 33. Upon 80 rotation of the hand wheel 15 in a clockwise direction, similar rotation of course will be imparted to the staff 12, which in turn effects rotation of the pinion 17. The pinion 17 meshing with the upper teeth of the gear 85 member 18, causes rotation of the gear member 18 about its axis. Rotation of the gear member 18 is transmitted to the pinion 34 mounted upon the winding drum 26, which 90 effects rotation of said drum about its axis to take up the slack in the brake rigging. When a predetermined resistance is reached, the parts begin to bind due to the increased 95 tension thereon, increasing the frictional resistance to such an extent that the winding drum 26 ceases to turn upon its own axis, and further rotation of the gear member 18 carries the winding drum 26 therewith, causing 100 swinging of the arms of the cylindrical member 21 in a clock wise direction, until the por-

tion 28 of the brake chain comes into engagement with the cylindrical portion thereof, the offset 23 providing for lateral movement of the lower leg 31 of the brake chain beyond the plane of the surface of the cylindrical portion. After the leg 28 of the chain has come into contact with the cylindrical member 21, it will be appreciated that further take-up of the chain is only at a speed co-incident with the rotation of the cylindrical member, which is very small resulting in a much slower movement with greatly increased power. The angle through which the member 21 turns, in operation, after the slack is taken up, is necessarily small, probably less than a revolution, due to the small distance the rigging will move after the slack is taken up and the shoes begin to approach the wheels.

While I have herein shown and described what I now consider the preferred manner of carrying out the invention, the same is merely illustrative, and I contemplate all changes and modifications that come within the scope of the claims appended hereto.

25 I claim:

1. In a hand brake, the combination with a driving mast, and brake rod, said mast being provided with a driving pinion thereon; of a ring gear rotatably mounted on an axis offset relative to the axis of said mast, said ring gear having engagement with said driving pinion and adapted to be driven thereby; an element mounted for rotation co-axially with said ring gear and being provided with radial extensions; a second element mounted for rotation on its axis upon said extensions, adjacent the ends thereof, said second element being provided with a pinion meshing with the teeth of said ring gear; a brake chain having an intermediate portion connected to said brake rod, one end of said chain being connected to said radial extensions, and the other end to said second rotatable element; and stop means adapted to limit movement of said extensions toward said brake rod.

2. In a hand brake mechanism, the combination with winding means comprising two winding elements rotatable about individual axes, off-set with respect to each other, one of said elements being a supporting element and having means upon which the other element is supported; of a brake-rod; a chain looped and movably connected intermediate its ends to said brake rod, one end of said brake chain being connected to the means of the supporting element upon which the supported element is mounted, and the other of said ends being connected to the supported element; and means mounted to rotate about the axis of the supporting element for rotating said supported element about its axis to wind the chain thereon to take up slack in the brake rigging, and effect bodily movement therewith of said supported element about the axis of the supporting element upon the re-

sistance to winding increasing to an extent to arrest rotation of said supported element about its axis, thereby carrying the means upon which said supported element is mounted therewith and effecting rotation of the supporting element about its axis to wind said brake chain thereon.

3. In a hand brake, the combination with a rotatable winding element provided with a pair of spaced laterally extending arms; of a second winding element rotatably mounted adjacent the free ends of the arms of said first element, said second element being movable in an orbital path about the axis of the first element during one phase of operation, and being rotatable about its own individual axis in another phase of operation; a brake-chain connected to said second element and adapted to be wound thereon when rotated about its individual axis, and adapted to be wound upon said first element during orbital movement of said second element about the axis of said first element; and means for effecting rotation of second element about its individual axis or orbital movement about the axis of said first element, dependent upon different degrees of tension in the brake chain.

In witness that I claim the foregoing I have hereunto subscribed my name this 10th day of February, 1926.

JOHN F. O'CONNOR.
